UNITED STATES PATENT OFFICE.

RICHARD R. CARDALL, OF SALT LAKE CITY, UTAH, ASSIGNOR OF ONE-HALF TO
HARRY SHEPHERD, OF SALT LAKE CITY, UTAH.

POSTING-TRAY AND RECORD-BINDER.

1,348,781.

Specification of Letters Patent.

Patented Aug. 3, 1920.

Application filed June 8, 1918. Serial No. 239,049.

To all whom it may concern:

Be it known that I, RICHARD R. CARDALL, a resident of Salt Lake City, in the county of Salt Lake and the State of Utah, have invented a certain new and useful Posting-Tray and Record-Binder, of which the following, together with the accompanying drawings, constitutes a full, clear, and exact specification, which will enable others skilled in the art to which it appertains to make and use the same.

My invention relates to a combined posting-tray and record binder designed primarily for use in connection with modern systems of mechanical book-keeping, and its principal objects are to provide an improved device which shall:

First: Be adaptable for use, either with the improved posting-box and file, for which I have made application for U. S. patent, filed April 9th, 1918; Serial No. 227,558, or for use in connection with various existing types of posting holders;

Second: Facilitate the convenient manipulation of invoices, bills and other record sheets on which it is required to make entries from time to time;

Third: Securely and compactly hold the sheets when the device is used as a binder or file, while at the same time permitting ready access to the sheets for purposes of reference;

Fourth: Be a combined tray for posting and a binder for records, which may be converted from the one use to the other, or back again, by simply a movement of the operator's hand;

Fifth: Not render it necessary to prepare the sheets in any special manner, such as forming perforations or notches therein in order to make them engage some certain part of the binder;

Sixth: Be simple in construction and not liable to get out of order when used by the average run of office help;

Seventh: Occupy a minimum of valuable vault space;

Eighth: Be economical to the purchaser and which shall be durable and efficient when in use.

In attaining these objects, a folding tray is provided, consisting essentially of two flat members or leaves hinged together along one edge thereof and adapted to be set at proper angles, with relation to each other,

according to the purpose for which the device is being used. The tray may be supported on a horizontal surface by any suitable means.

An adjustable member, which I choose to term the "follower," is provided, which may be arranged to slide over one of the leaves and be adjustably clamped thereto, thus forming a space between the follower and the other leaf, into which space record sheets may be placed and be tightly held when the device is used as a binder for filing away the sheets.

The leaf, on which the follower is clamped, may be made extensible, so as to provide a larger capacity for the binder, while, at the same time, not occupying the maximum amount of space, unless it is actually required.

Small wheels or rollers may be provided, so that the device, with its contents, can be easily rolled over a flat surface, which proves convenient when it is to be placed into limited compartments in the ordinary safe or vault.

The leaf against which the sheets rest, and a portion of the follower, may be made so as to open away from each other at the top, in order to allow a convenient amount of room in front of the particular sheet which is being referred to.

The features on which protection is desired are collectively grouped in the appended claims.

In the drawings, which illustrate merely one embodiment of this invention:

Figure 1 represents a plan view of the same used as a binder;

Fig. 2, a side elevation thereof;

Fig. 3, a section on line 3—3 in Fig. 2, looking in the direction of the arrows; and

Fig. 4, a section through an ordinary posting holder, showing the present device set thereinto in the posting position.

Referring to the drawings, 10 and 11 are leaf members pivoted to each other at 12. Member 11 has the extensible portion 13, on which may be slidably disposed an adjustable follower 14. The follower may be provided with an adjustable rest consisting in this instance of a plate 15, preferably of metal pivoted at 16 and having the co-acting catches 17 and 18 (Fig. 3), which are pivoted to the plate 15, at 17^a and 18^a, and which are adapted to engage suitably placed

notches; for instance, 20 and 20^a (Fig. 2) in the follower 14. A pin 19 rigidly fastened in the catch 17 may engage a slot 38 formed in the catch 18. At 21 is a spring for holding the catches 17 and 18 in the normal position in engagement with the sides of follower 14, as shown by full lines in Fig. 3. The dotted lines in Fig. 3 show the positions of the catches 17 and 18 when they are disengaged. At 22 is a tie between the sides of follower 14 for the purpose of stiffening the same. In order to allow the follower 14 to be adjustably positioned, a guide strip 24 may be attached to the middle slat 13^b of the extension 13, as shown in Fig. 3. Clips 25 may extend through slots in the bottom of follower 14 and may have their lower portions formed to grip the under side of guide 24. An eccentric clamp 26 may be pivoted in the clips 25 and be adapted to draw these up to the guide 24, thereby forcing the follower tightly against the guide 24.

The leaf portion 10 may have pivoted thereto, at 27, the side bars 28, which latter may have the notches 28^a, 28^b and 28^c and the projecting lug 29. A bar 30 may connect the various slats 11^a forming parts of the leaf 11 and this bar may have two ends upturned in order to support the pins 31. Small wheels or rollers 32 may be journaled on the shaft 12 and a roller 33 may be provided at the outer end of the extension 13, as shown in Figs. 1 and 2.

A bar 35 (Figs. 1 and 2) may connect the slats 11^a, and a thumb screw 36 threaded in a bushing 37 may be provided for clamping the extension 13 to the leaf 11.

In using this device as a posting tray (Fig. 4), it may be set into any ordinary holders such as are in general use at the present time, or if desired, any other suitable means may be employed to support the tray in a convenient position similar to that indicated in Fig. 4. As here shown, the side bars 28 play no part, merely resting on the apex of the holder partition. In cases where this tray would be used with the improved posting-box and file already referred to, the notch 28^c would be used to engage the pin 31 in order to secure the proper angle between the leaves 10 and 11, as described in the application for patent mentioned.

In using this device as a record binder, (Figs. 1 and 2), the leaf 10 would ordinarily be in a position at right angles with the leaf 11 and would be held in that position by the side bars 28, the latter having the notches 28^b in engagement with the pins 31, while the stack of records 34, would be set on edge on the leaf 11 and rest against the leaf 10, with the follower 14 pressed closely up against the opposite face of the stack and clamped in position by the eccentric 26.

At such times when it may be desired to consult any of the records in the binder, the

pin 19 may be grasped by the fingers of the operator, the catches 17 and 18 released from the notches 20, the plate 15 be moved to the position 15^a and catches 17 and 18 brought into engagement with the notches 20^a. Further, the lugs 29 of the side bars 28 may be grasped by the fingers of the operator and the leaf 10 be brought to the position shown by the dotted lines in Fig. 2, at which time, the notches 28^c would be in engagement with the pins 31, the position of the side bars 28, in this case, being indicated by the dotted lines.

The stack of records 34 can now be divided into two suitable portions 34^a and 34^b and the various sheets fingered back and forth from one portion to the other until the required sheet is found and this can then be conveniently consulted, owing to the ample angular space between the two portions. As a binder, this device may have a very flexible capacity and may be extended to any reasonable limit, as shown by the position of the movable parts 13^a and 14^a indicated by dotted lines in Figs. 1 and 2.

While a satisfactory embodiment of this invention is here shown and described, all the detailed parts thereof are not necessarily in the preferred form.

What I claim is:

1. In a posting-tray and record binder, the combination of a leaf portion with a second leaf portion pivotally connected thereto, a follower movably mounted on the second leaf portion and so arranged that record sheets may be confined between the said first leaf portion and the said follower; and members for rigidly holding the two leaf portions in variable positions with relation to each other.

2. In a posting-tray and record binder, the combination of a primary leaf portion having pivotally connected thereto a secondary leaf portion, a follower member movably mounted on the secondary leaf portion, the said follower member being attachable when the device is used as a file and detachable when the device is used as a posting tray, and arms fastened to the primary leaf portion, the said arms at the same time adjustably engaging the secondary leaf portion in such a manner that the primary leaf portion may be moved in a direction away from the follower when the device is used as a record binder, and in a direction toward the secondary leaf portion when the device is used as a posting-tray.

3. In a device of the kind described, the combination of a primary leaf portion with a pivotally connected secondary leaf portion, a follower member adjustably mounted on the secondary leaf portion, the said follower member being attachable when the device is used as a file and detachable when the device is used as a posting tray, and

- means for holding the primary leaf portion in a position where it makes an angle of more than 90 degrees with the secondary leaf portion when the follower is attached to the latter, and for holding the primary leaf portion in a position where it makes an angle of less than 90 degrees with the primary leaf portion when the follower is detached from the secondary leaf portion.
- 10 4. In a posting-tray and record binder adapted to confine certain contents, the combination of a primary leaf portion, a secondary leaf portion, flexibly connected thereto, an adjustable follower member slidably mounted on the secondary leaf portion, the said follower being attachable when the device is used as a binder and detachable when the device is used as a posting-tray, and adjustable arms for rigidly holding the said leaf portions, first, in a "reference position" with relation to each other when the said follower is attached, and, second, in a "posting position" with relation to each other when the said follower is detached.
- 15 5. In a posting-tray and record binder, the combination with a primary leaf portion, of a secondary leaf portion pivotally connected thereto along adjacent edges thereof, an adjustable follower suitably mounted on one of the said leaf portions, and means for adjustably limiting the angular opening between the said leaf portions.
- 20
- 25
- 30

6. In a posting-tray and record binder, the combination with two suitably interhinged leaf portions, of a guide attached to one of the said leaf portions, a follower adjustably mounted on the said guide, a movable rest positioned on the said follower, means for adjusting the said movable rest and means for adjusting the angular opening between the said leaf portions.

7. In a posting-tray and record binder, the combination with two suitably interhinged leaf portions, of an extension member coöperatively disposed on one of the said leaf portions, a guide positioned on the said extension member, a follower adjustably mounted on the said guide, and means for adjusting the angular opening between the said leaf portions.

8. In a posting-tray and record binder, the combination with two suitably interhinged leaf portions, of an extension member coöperatively disposed on one of the said leaf portions, a guide fixed on the said extension member, a movable follower adapted to engage the said guide and to be clamped thereto, a movable rest positioned on the said follower, means for holding the said movable rest in predetermined positions and means for adjusting the angular opening between the said leaf portions.

RICHARD R. CARDALL.
